ABSTRACT: A tool for facilitating the pulling of strands between spaced supports to which the strands are to be attached which consists generally of a handle with a grooved pulley mounted thereon and a rotatable key mounted on the handle adjacent the pulley which may be turned from an open position to permit placing a loop of the strand over the pulley to a closed position to prevent the strand loop from leaving the pulley when not in taut condition and the method of pulling strands using said tool which includes the steps of fastening the ends of strands being fed from storage rolls to one support adjacent the storage rolls, looping said strands over the pulley, pulling the tool with the strands looped over the pulley to a second support and finally fastening the strands thus pulled to the spaced supports.

WIRE PULLING TOOL

This invention relates to a tool for pulling strands and to a method of pulling strands using such tool.

There are certain installations in which strands are stretched between and fastened to spaced supports in taut condition. One such installation of common knowledge is in wire fences in which wires are stretched between fence posts and fastened thereto. Another is in telephone wiring installations such as may occur in telephone exchanges or in underground vaults where various connections are made between the wires of telephone cables. In the case of the latter, it is common practice to provide a frame having spaced end pieces with wires stretched in parallel fashion across the frame and fastened to the end pieces.

The tool of my invention facilitates the placement of wires in installations such as given above by way of example, but it obviously may be used in any installation where a number of wires or strands must be placed between fixed spaced supports.

It is one object of my invention to provide a simple yet practical tool for extending and placing strands such as wires between spaced supports.

It is another object to provide such a tool which may accommodate a number of strands at a time.

It is still another object to provide a novel method of extending and placing strands using the novel tool.

These and other objects and advantages will become more apparent as this description proceeds and reference is had to the accompanying drawing forming a part of this specification and in which:

FIG. 1 is a perspective view of my novel strand stretching tool;

FIG. 2 is a sectional view on the line 2—2 of FIG. 1 of the pulley end of the tool with the pulley removed from the handle; and

FIG. 3 is a view of a frame such as used in telephone wiring installations showing the use of the tool in extending or stretching wires to be fastened to said frame.

Referring now to the drawing in detail, the tool comprises a pulley 10 provided with a peripheral groove 11 rotatably mounted on a handle member 12 by means of a bolt 13 and nut 14. The free end of the handle 12 is preferably provided with a transverse hand grip 15 to facilitate pulling.

On the handle 12 adjacent the pulley a rotatable key 16 is mounted, which key in one position will afford access to the groove in the pulley so that a strand loop may be placed over the pulley and in the groove and in another position will substantially cover the groove to prevent the loop from slipping out.

The key 16 is rotatably mounted on the handle 12 by means of the bolt and nut 18 and in order to minimize the number of projections on the tool which might inadvertently snag or catch on the strands as the loops are placed on the pulley and the tool advanced, it is preferable to countersink both the nut 18 and the nut 14 mounting the pulley on the handle, as shown.

FIG. 3 shows the method employed in using the tool. In this instance the strands are wires which are to be attached in parallel relation on a frame such as is used in telephone wiring assemblies.

The frame 22 is rectangular and has parallel end pieces 23, 23' between which parallel wires are to be stretched and fastened at points 24 on the end pieces.

To place the wires by means of the tool a number of rolls or spools 26, 26' of wires are first positioned adjacent one end piece 23' of the frame and are mounted so that they may freely feed off wire when the ends of the wires are pulled. The ends of the wires from as many spools as desired are then fastened at points 24 on the end piece 23' of the frame. Loops 10 are then formed in the wires between the spools and their fastenings 24 on the end piece and said loops are placed over the pulley 10 of the tool and the key 16 turned to a position to prevent the loops from slipping out of the groove in the pulley. The tool is then advanced along the frame to the opposite end piece 23 where the wires are then cut and fastened at points 24 thereon and the wires cut at the spools and the ends from the loop fastened at 24 on first end piece 23'. It can readily be seen that for each spool or roll of wire one advance of the tool across the frame results in two wires being stretched simultaneously. Obviously a number greater than two may be placed by a single passage of the tool across the frame by providing a greater number of rolls or spools so long as the loops over the pulley are placed in the same direction.

Having described my invention what I desire to secure by Letters Patent is:

1. The method of pulling strands and fixing them to spaced supports therefor which includes the following steps:
  - a. rotatably mounting at least one supply roll of the strand material adjacent one of the spaced supports whereby the strand may be fed from the roll by pulling the end thereof;
  - b. fastening the end of said strand to said one support;
  - c. forming a loop in said strand between the point of attachment of said strand to said one support and the supply roll;
  - d. placing said loop over a pulley rotatably mounted on a pulling tool;
  - e. advancing said pulling tool from adjacent said one support toward the other of said spaced supports and thereby feeding said strand from said supply roll and advancing said loop in the strand to a point slightly beyond said other support;
  - f. fastening the strand on both sides of the loop to said other support; and finally
  - g. fastening said strand fed from said supply roll to said first support.
2. A portable tool for pulling strands comprising:
  - a. a handle member;
  - b. a grooved pulley member rotatably mounted on the handle adjacent one end thereof;
  - c. a handle grip at the end of the handle opposite the end mounting the pulley perpendicular to the axis thereof; and
  - d. a rotatable key mounted on the handle having its axis parallel with the axis of the pulley which in one position of rotation extends over and in proximity of the pulley groove to prevent lateral entry and removal of a strand to the groove and in a second position is removed from proximity of the groove to permit such entry and removal of the said strand.
